UNITED STATES PATENT OFFICE.

FREDERICK SAGER, OF ROCHESTER, NEW YORK.

DESIGN FOR A GARMENT-HANGER.

SPECIFICATION forming part of Design No. 30,231, dated February 21, 1899.

Application filed January 28, 1899. Serial No. 703,741. Term of patent 7 years.

To all whom it may concern:

Be it known that I, FREDERICK SAGER, a citizen of the United States, and a resident of Rochester, in the county of Monroe and State 5 of New York, have invented and produced a certain new and original Design for a Garment-Hanger, of which the following is a specification.

The drawing represents a perspective view 10 of a garment-hanger embodying my design.

The design consists in the shape and configuration of the garment-hanger herein shown and described.

In the drawing the garment-hanger has at 15 the bottom two straight parallel members a a , which at equal distances from their middle points are bent upwardly at each end at right angles to the parallel portions as shown at a' . Adjacent to the bends a' the two members 20 diverge in the curves a^1 a^2 and thence continue upwardly in the straight parallel portions a^3 a^4 , merging into the coiled portions a^5 . Near the upper ends of the coiled por-

tions a^4 the garment-hanger continues in single members, which are bent at a^5 at right 25 angles to the coiled portions, and the two members a^6 a^7 extend straight toward each other and meet at a point substantially halfway between the bends a^5 . Thence the garment-hanger continues upwardly in the single 30 coiled portion a^7 , from which the loops a^8 extend in opposite directions, being arranged symmetrically with reference to the same plane as the parts a^6 a^7 and a . In line with the coiled portions a^7 the garment-hanger continues upward in the coiled portion a^9 , whence 35 it continues and terminates in the hook-shaped portion a^{10} .

What I claim is—

The design for a garment-hanger as herein 40 shown and described.

FREDERICK SAGER.
